FLOOR PROCESSING MACHINE

Walter S. Finnell, Elkhart, Ind.

Application October 30, 1947, Serial No. 783,185

2 Claims. (Cl. 91—25)

1

The present invention pertains to improvements in Floor Processing Machines.

An object of the invention is to provide an electrically operable rotary processing device including improved weight distribution.

A further object is to provide a device of the above nature including an electric driving motor mounted vertically in the rear of the machine and operatively connected to the rotary brush spindle so as to drive the latter at reduced speed without the use of gearing.

A further object is to provide a device of the above type including a double reduction V-belt drive from the driving motor and the rotary brush spindle.

Another object is to provide a rotary processing device including means to feed hot wax, water or other fluids through the middle of the rotary brush rather than to the outer circumference thereof.

A further object is to provide improved means for attaching a rotary brush to its driving spindle.

A still further object is to provide ratchet latching means between the operating handle and the body of the scrubber, whereby the handle may readily be set at any desired operating angle for operating the device, changing brushes, etc.

Further objects and advantages of the invention will become evident during the course of the following description in connection with the accompanying drawings in which:

Figure 1 is a longitudinal part sectional view of a preferred form of scrubber, with the handle removed;

Figure 2 is a plan view of the same;

Figure 3 is a side elevation of the complete machine illustrating the provision of means to feed water or other fluids to the center of the brush;

Figure 4 is a bottom illustration of a typical rotary brush illustrating the central feed feature;

Figure 5 is a detail plan view of a typical brush hub;

Figure 6 is a similar view partly cut away, to illustrate the improved means of attaching the brush to its spindle and preventing accidental release of the brush therefrom; and

Figure 7 is a detail cross sectional view of the brush hub in the plane 7—7, Figure 6.

Referring to Figures 1 and 2, the numeral 10 denotes a casing open at the bottom and having a substantially circular forward portion 11 and a rectangular rear portion 12. A downwardly directed bearing sleeve 13 is secured in the cir-

2

cular portion 11 so as to be concentric therewith. A spindle 14 is supported on roller bearings 15 and 16 in the sleeve 13. The spindle 14 has formed integrally therewith or secured thereto a flange 17, and terminates in a substantially rectangular cross member comprising laterally extending driving dogs 18. A central passage 14a extends through the spindle 14. A V-belt pulley 19, herein illustrated as adapted to accommodate twin V-belts 20 and 21, is secured to the flange 17.

A downwardly directed pin 22 is secured in the casing 10 rearwardly of the spindle 14 and is braced rigidly by means of a bracket 23. The pin 22 carries bearings 24 and 25, preferably of ball type, on which is mounted a double diameter V-belt sheave 26. The small portion 27 of the sheave 26 is aligned with the spindle pulley 19 and is connected therewith by means of the V-belts 20 and 21.

An electrical motor 28, having a vertical shaft 29, is mounted on top of the rectangular casing portion 12 with the shaft 29 protruding downward within the casing. A pulley 30 of comparatively small diameter is operatively connected by means of twin V-belts 31 and 32 with the large portion 33 of the intermediate or jack sheave 26.

A cross axle 34, carrying a pair of wheels 35, is disposed under the rear of the rectangular casing portion 12 so that the major weight of the motor 28 may be carried by the wheels 35.

A socket 36 is hinged at 37 to a bracket 38 secured on the upper rear extremity of the casing portion 12. A handle shank 36a is removably clamped in the socket 36. The bracket 38 and casing portion 12 are slotted at 39 to allow the passage of a curved ratchet member 40 which is pivoted at 41 to the socket 36. The member 40 is provided with two or more downwardly directed ratchet notches 42 adapted to engage the lower edge 43 of the slot 39.

A rotary brush 44, preferably of a sectional type as illustrated in Figure 4, and comprising any desired number of segments 45 is secured to the spindle 14 in the following manner:

The supporting disc portion 46 of the brush 44 has a central circular flange 47 embracing and secured to a hub 48. The hub 48 is constructed with an upper elongated opening 49 (Figures 5, 6 and 7) adapted to admit the driving dogs 18 axially, while the interior 50 of the hub comprises arcuate recesses 51 and 52 adapted to permit the dogs to be revolved through approximately ninety degrees within the hub until they engage abutments 53 and 54 as illustrated in

Figure 6. In this position the upper walls of the recesses overlie the dogs and prevent their axial withdrawal after the manner of a bayonet joint.

Referring to Figure 6, the numeral 55 designates a small plunger slidably mounted in a hole 56 in the hub 48 and provided with a necked portion 57 carrying a compression spring 58. The neck portion 57 extends outward through a small lug 59 struck out from the flange 47. A button 60 on the end of the neck portion 57 restrains the plunger 55 from excessive inward movement under pressure of the spring 58.

The end 61 of the plunger 55 extends diagonally into the recess 53. When it is desired to mount the brush 44 on the spindle 14, the driving dogs 18 are inserted through the elongated opening 49 so as to register laterally with the recesses 53 and 54. The driving dogs 18 are then rotated into the recesses either by turning the spindle counter-clockwise (Figure 6) or by rotating the hub 48 in the opposite direction. During this relative rotation, one of the dogs 18 engages the end 61 of the plunger 55 and forces the latter outward against the pressure of the spring 58. When the dog 18 has completely overridden the plunger 55 and has reached the position illustrated in dot-dash lines of Figure 6, the plunger 55 snaps in behind it.

It is evident that thereafter, any tendency of the bar 18 to revolve clockwise, that is, in reverse direction in the hub 48, causes the dog to engage the side of the plunger-latch 56 which restrains further movement and prevents accidental disengagement through reverse motion.

When it is desired to remove the brush from the spindle, the plunger 55 is pulled outward manually by means of the button 60, thus releasing the dog 18 and allowing the brush to be revolved until registry of the dogs with the opening 49 permits removal of the brush from the end of the spindle. The hub 48 has a lower central opening 62 for a purpose hereinafter set forth.

Referring again to Figure 1, an electrically operated wax heater 63 may be mounted by means of a bracket 64 on the top of the casing 10 ahead of the motor 28. The heater 63 has a lower tubular connection 65 extending downwardly into the central passage 14a in the spindle 14. Since the heater 63 may be of any suitable type of which the particular internal construction comprises per se no part of the present invention, description of the particulars of its internal parts need not be included herein.

It is evident that when fluid wax from the heater 63 is admitted by the connection 65 to passage 14a, the wax flows down through the hollow spindle and the opening 62 in the hub 48 into the space within the central zone of the brush 44.

Figure 3 illustrates the general construction of the device as described except that instead of the wax heater 63 being provided on the top of the casing 10, a tank 66, suitable for containing water or other processing fluid, is secured on the handle shank 36a. A flexible tube 67 connects the tank 66 with an angular fitting 68 securely on the casing 10 and adapted to deliver fluid into the hollow spindle as previously described.

The tank 66 is provided with a flared filler top 69. A rod 70, adapted to operate a valve 71 of any suitable type for controlling the flow of fluid from the tank 71 through the tube 67, 78 or care in moving the parts together. As an

extends upward to a point near a pair of operating hand grips 72. The grips 72 extend laterally from a switch box mounted on the outer end of the handle shank 36a. Switch control levers extend from the switch box 73 in convenient position adjacent the hand grips 72.

In processing a floor by means of the machine, the operator grasps the grip 72 and turns the motor on and off as desired by means of the switch layers 74. In ordinary operation it is normally convenient to push the machine about with the handle at comparatively low angle and freely movable up and down. To provide for this operation, the arcuate latch 40 may be pushed forward and upward by the operator's foot to release the notches 42 from the latching edge 43 as previously described. The handle may then be swung downward until the un-notched portion 40a of the latch rides freely on the edge 43.

Should it be desired to raise the brush 44 from the floor as, for instance, in travelling over a door sill or the like, the handle may be pushed upward until the rearmost notch 42 engages the latching edge 43 to support the handle shank 36a in the position shown in Figure 3. The operator then pushes downward on the hand grips 72. The wheels thereupon act as a fulcrum and as the weight of the processing machine is distributed by location of the motor 28 near the wheels 35, the machine is readily swung upward to allow the brush 44 to clear the floor or obstruction.

When it is desired to store the machine in a minimum of space, the handle shank 36a may be swung to vertical position, the forward notch 42 of the latching member 40 engaging and holding on the latching edge 43 as illustrated in Figure 1.

The weight distribution noted above also is advantageous when it is desired to install the brush 44 or to change from one type of brush to another, since the forward part of the machine is readily swung up from the floor in the manner described above.

In removal of the brush 44, the latch plunger 55 (Figure 6) is drawn outward by means of the button 60 to release the dogs 18, allowing the brush to be revolved in approximately ninety degrees until the cross opening 49 registers with the dogs 18, whereupon the brush may be withdrawn axially.

It will be noted in Figure 1 that the upper and lower surfaces 18a and 18b of the dogs 18 are slightly inclined toward each other so as to provide a tapering clearance between them and the upper and lower walls of the recesses 54. Also, the ends and corners of the dogs will be seen to be rounded and that they clear the outer walls of the recesses. This construction allows the brush 44 to have a limited amount of freedom to rock or float on the end of the spindle 14. By this means, during operation of the device, the attaching means of the brush to the spindle operates after the manner of a universal joint, permitting the brush 44 to ride flat on the floor while the body of the device may be tipped at varying small angles to vary the downward processing pressure or when the wear of the brush has made downward inclination of the body necessary to maintain proper contact.

It will be seen that the shape of the driving dogs 18 as described is such as to facilitate their entry into the hub 48 without undue precision or care in moving the parts together. As an

example, if desired in installing a brush, the latter may be placed flat on the floor, the machine tipped upward and lowered until the lower end of the spindle rests approximately in the center of the hub 48. If thereupon the spindle 14 is rotated by momentary operation of the motor 28, the tapered dogs 18 drop readily into the cross opening 49 and revolve into lock position in the recesses 53. In other words, when the brush is applied in the manner described, the entry and locking of the attaching means is automatically accomplished as the motor revolves the brush in driving direction.

The brush 44 may be of any desired type to accomplish various processing operations such as scrubbing, surfacing, waxing, etc. In accomplishing operations in which it is desired to apply a fluid to the floor, the fluid is admitted through the middle of the brush by the means previously described.

It is obvious that this means of applying a fluid, such for example as hot wax, is much superior to methods in which the fluids are applied to or outside the periphery of the brush, since the fluid works evenly out under all brushing surfaces and is not pushed or thrown about on walls, baseboards or the like. With proper regulation of the fluid feed, no undue surplus fluid is released to accumulate on the floor outside the brush circumference and to require subsequent removal. The central feed thus provides maximum efficiency and economy in utilization of fluid.

The V-belt structure described provides a quiet, gearless drive in minimum space, the double-reduction feature permitting a large over-all speed reduction with comparatively small closely spaced sheaves and with moderate individual reductions, thus ensuring ample arcs of belt contact on all sheaves.

While the invention has been described in preferred form it is not limited to the exact embodiments illustrated, as various changes and modifications can be made without departing from the scope of the appended claims.

What is claimed is:

1. In a device of the character described, in combination, a casing, a vertical spindle rotatably mounted in the forward portion of said casing and having a central passage, a motor secured on the rear portion of said casing and having a vertical shaft extending downward in said casing, speed-reducing means including V-belts operatively connecting said shaft and said spindle whereby said motor may drive said spindle at 55

reduced speed, a hub underlying the lower end of said spindle, a driving member on the lower portion of said spindle and engaging said hub in rotary driving relation, said hub being laterally rockable on said member, means to retain said hub on said member, said hub having an unrestricted central aperture in axial registry with said passage, an annular brush plate secured to the periphery of said hub, means forming a substantially annular brush secured to said plate and adapted to engage a floor, a wax heater on said casing, and means to conduct melted wax from said heater to the top of said passage, whereby said wax may pass downward in unobstructed flow through said passage and said central aperture in said rockable hub to said floor at the center of said annular brush.

2. In a device of the character described, in combination, a support, a rotary spindle vertically journaled in said support, a driving member on the lower end of said spindle, a hub engaging said driving member in rotary driven relation, said hub being laterally rockable on said member, means to retain said hub on said member, a substantially annular processing member secured to said hub and adapted to engage a floor, means forming an unobstructed central passage for processing fluid through said spindle and said rockable hub, means to rotate said spindle, and means to direct a processing fluid through said unobstructed passage to said floor at the center of said processing member.

WALTER S. FINNELL.
